Primary Examiner—Susan Bennett Hattan*(74) Attorney, Agent, or Firm*—Fulbright & Jaworski(57) **CLAIM**

The ornamental design for a container cap, as shown and described.

DESCRIPTION

FIG. 1 is a top perspective view of my design comprising a container cap with multiple components illustrated with a fully assembled view and an exploded view;

FIG. 2 is a bottom perspective view illustrated with a fully assembled view and an exploded view;

FIG. 3 is a front view illustrated with a fully assembled view and an exploded view;

FIG. 4 is a back view illustrated with a fully assembled view and an exploded view;

FIG. 5 is a left side view illustrated with a fully assembled view and an exploded view;

FIG. 6 is a right side view illustrated with a fully assembled view and an exploded view;

FIG. 7 is a top view; and,

FIG. 8 is a bottom view.

The dashed lines in FIGS. 2 and 8 represent environmental structure and form no part of the claimed design. All other surface(s) or portion(s) of my design not shown in the figures or otherwise described in the specification form no part of the claimed design.

1 Claim, 7 Drawing Sheets# US D604,160 S
